UNITED STATES PATENT OFFICE.

JOHN F. O'CONNOR, OF CHICAGO, ILLINOIS, ASSIGNOR TO WILLIAM H. MINER, OF CHAZY, NEW YORK.

TANDEM SPRING DRAFT-RIGGING FOR RAILWAY-CARS.

1,283,544.

Specification of Letters Patent.

Patented Nov. 5, 1918.

Application filed October 25, 1916. Serial No. 127,513.

To all whom it may concern:

Be it known that I, JOHN F. O'CONNOR, a citizen of the United States, residing at Chicago, in the county of Cook and State 5 of Illinois, have invented a certain new and useful Improvement in Tandem Spring Draft-Rigging for Railway-Cars, of which the following is a full, clear, concise, and exact description, reference being had to the 10 accompanying drawings, forming a part of this specification.

My invention relates to tandem spring draft rigging for railway cars.

The object of my invention is to provide 15 an efficient means for securing follower supporting plates to tandem draft rigging side plates.

In the drawings forming a part of this specification, Figure 1 is a side elevation of 20 a draft rigging embodying my invention; Fig. 2 is a cross section taken on line 2—2 of Fig. 1; Fig. 3 is a perspective view of one of the brackets; Fig. 4 is a view taken at the center post of a tandem draft rigging 25 side plate showing a modification.

In the drawings forming a part of this specification, the numeral 5 indicates center sills or stop members, being the part of the car underframe to which the draft rigging 30 is applied. The side plates (sometimes called side castings, or stop castings, or cheek plates) 6—6 are secured to the draft members by suitable means, as, for instance, the rivets 7—7. Each side casting comprises a 35 plate having the front post 8 forming the front stop shoulder 9, the middle post 10 forming the front middle stop shoulder 11 and rear middle stop shoulder 12, a rear post 13 forming the rear stop shoulder 14. The plate is also provided with the front 40 and rear limiting stops 15 and 16, respectively. Mounted between the side plates are the front and rear compression resisting devices 18 and 19, respectively, each comprising a pair of followers 20—20 and the interposed springs 21. The yoke 22 secures the compression resisting devices to the drawbar 23. Each casting is provided with an upper guide flange 25 and a lower follower 50 supporting plate 26. Each stop casting is provided along its lower portion with a horizontal flange 27, the said flanges being provided at the main posts 8, 10 and 13 with vertical perforations 28, each for the passage 55 of the shank 29 of a bracket 30. The

said vertical perforations 28 open laterally as at 31—31, each to permit the lateral insertion of a bracket 30. The said lateral openings are constricted at their lower portions 32, and are wider at their upper portions 33, the said upper portions being adapted to permit the lateral insertion and removal of the head 34 of the bracket 30, and the lower constricted portion is adapted for the lateral passage of the shank 29 of the bracket 30. Each of said brackets is 60 provided with a longitudinal perforation 35 for the passage of the follower supporting plate 26. The upper or wider portion 33 of each of said lateral openings is sufficiently extended vertically to permit the transverse insertion of the head 34 of the bracket 30, and when inserted the said bracket is adapted to be forced downwardly 70 until the shoulder 36 thereof is engaged against the shoulder 37 provided upon the casting, and when in this position the upper edge 37 of the slot 35 in the bracket is substantially in alinement with the lower faces 75 of the posts 8, 10 and 14 of the side casting. The said brackets when inserted are adapted 80 to receive the follower supporting plate 26 which is threaded through all of said brackets, and when in its follower supporting position is prevented against accidental 85 displacement by means of the head 39 provided on one end thereof, and securing means, as, for instance, the cotter 40 provided in the other end thereof.

It will be observed that the use of these 90 brackets dispenses with the necessity of long bolts extending through the side plate vertically, which tends to weaken the same, permits the ready and easy removal of the 95 follower supporting plates and of the brackets, and permits such removal and replacement when the other parts of the draft rigging, including the springs and followers, are in their assembled position in the draft rigging.

It will also be observed that the space between the transverse flanges 41 of the side casting and the lower flange 27 is very small, and that my device permits the securing of the follower supporting straps to the 105 casting without cutting or otherwise weakening the flange 41.

In Fig. 4 of the drawings, a modified form of means for securing the follower supporting strap in the brackets is shown.

100

105

110

In said figure the numeral 42 indicates the central main post of a casting, 43 the upper flange, 44 the rear intermediate follower, 45 the front intermediate follower, 46 the follower supporting strap, 47 the downwardly and laterally opening slot in the bottom of the post 42, and 48 a tapered key, the follower supporting strap 46 passing through the perforation 49 in the bracket 54, and is at an adjacent point of its passage provided with an oblique face 50 against which the edge 51 of the tapered key 48 engages. The said tapered key is employed after the follower supporting strap is in place in the perforation 49 in the bracket for driving the follower supporting plate into close engagement with the bottom of the post and for holding the said strap within the bracket. The tapered key is secured against accidental removal by the transverse cotter or pins 52 passed therethrough.

I claim:

1. In a draft rigging for railway cars, a side plate having a bottom flange, laterally opening slots in said flange, removable brackets for said slots, and a follower supporting plate, the said brackets being provided with longitudinal perforations for the passage of said plate.
2. In a side plate for railway car draft rigging, the combination with main posts thereon, of downwardly and laterally opening slots in the lower edges of said posts, and a bracket mounted in each of said slots, the said brackets being provided with longitudinal perforations for the passage of a follower supporting strap.
3. In a draft rigging for railway cars,

the combination with a stop casting having posts forming stop shoulders, said posts having flanges at the bottom thereof, said flanges and one of the adjacent walls of the posts being slotted, of a follower guiding and supporting strap adapted to extend along the bottom of said casting, brackets insertible within said slots and having lugs thereon depending below the bottom of the casting, and integral coöperating means on said lugs and said strap to retain and support the latter in assembled relation with the stop casting.

4. In a draft rigging for railway cars, the combination with a stop casting having posts forming stop shoulders, said posts having flanges at the bottom thereof, said flanges being provided with openings therethrough, of follower strap supporting brackets insertible within said openings and having each an integral lug depending below the flanges, said lugs being recessed to permit insertion of a follower strap therethrough for supporting the latter.

5. As an article of manufacture, a bracket adapted to be detachably associated with a stop casting having a slot at the bottom thereof, said bracket having an enlarged head and a depending lug portion, the latter being slotted and adapted to receive a follower-carrying strap therethrough.

In witness that I claim the foregoing I have hereunto subscribed my name this 20th day of Oct. 1916.

JOHN F. O'CONNOR.
